(57) **CLAIM**

The ornamental design for a tip for ultrasonic handpiece for oral surgery, as shown and described.

DESCRIPTION

FIG. 1 is a front view of a tip for ultrasonic handpiece for oral surgery;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view from upper right side thereof.

The broken lines in FIG. 2 are included for the purpose of illustrating environmental structure of the tip for ultrasonic handpiece for oral surgery and form no part of the claimed design.
